United States Patent Office.

SMITH S. BROWN, OF WOONSOCKET, RHODE ISLAND.

Letters Patent No. 82,796; dated October 6, 1868.

IMPROVED CURTAIN-FIXTURE.

The Schedule referred to in these Letters Patent and making part of the same.

TO ALL WHOM IT MAY CONCERN:

Be it known that I, SMITH S. BROWN, of Woonsocket, in the county of Providence, and State of Rhode Island, have invented a new and valuable Improvement in Curtain-Fixtures; and I do hereby declare that the following is a full, clear, and exact description of the construction and operation of the same, reference being had to the annexed drawings, making a part of this specification, and to the letters and figures of reference marked thereon.

Figure 1 of the drawings is a representation of an external view of my device, and

Figures 2 and 3 are details.

My invention relates to that class of devices which are used for moving and sustaining window-curtains when in use.

The letter A of the drawings represents the window-frame upon which my device is placed.

Letter B is the roller on which the curtain is wound. This roller has its bearings, at each end, in upright ears attached to the movable head-plates, next mentioned, respectively.

Letter C is a slotted head-plate, attached to the window-frame by a thumb-screw, d, and serves the purpose of providing ready means for attaching and detaching roller B.

Letter D is also a slotted plate attached to the side of the window-frame by a thumb-screw, e. It is pivoted at its extreme upper end to a head-plate, E, set at right angles therewith, and serves the purpose of providing means, in connection with plate C, of attaching and detaching the roller, and also, in conjunction with plate C, of providing means for moving said roller upward or downward at will.

Letter G is a slotted plate attached to the window-frame, near the bottom of the window, and on one side thereof. It has a thumb-screw, marked h, by which it is held to the frame, and it is also pivoted to the swinging plate O, that holds the pulley-wheel for the cord at its lower end.

Letter Y is a pulley-wheel, adjusted as shown, and which, in conjunction with a suitable groove on the end of roller B, serves to hold and regulate the movements of the cord V. This cord V is adjusted in the manner shown and described, and when so adjusted, provides the means by which the operator raises or lowers the curtain.

It will readily be seen that, by means of the sliding grooved plates above mentioned, and their respective thumb-screws, the operator has it in his power to tighten or loosen the curtain to almost any extent he may desire, without any of the difficulties attending the ordinary mechanism used for that purpose.

The great merit of my invention consists mainly in the cheapness and simplicity of its construction and operation, and in the perfect manner in which its work is accomplished.

What I claim as my invention, and desire to secure by Letters Patent, is—

A fixture for window-curtains, having roller B, slotted plates C, D, and G, with their respective thumb-screws, head-plate E, swinging plate O, pulley Y, and cord V, constructed, combined, and arranged substantially as herein specified.

In testimony that I claim the above, I have hereunto subscribed my name in the presence of two witnesses.

SMITH S. BROWN.
